UNITED STATES PATENT OFFICE.

KENNETH HOWIE, OF PHILADELPHIA, PENNSYLVANIA, ASSIGNOR TO WILDMAN MFG. CO., OF NORRISTOWN, PENNSYLVANIA, A CORPORATION OF PENNSYLVANIA.

TAKE-UP MECHANISM FOR KNITTING-MACHINES.

1,399,121.

Specification of Letters Patent.

Patented Dec. 6, 1921.

Application filed March 3, 1919. Serial No. 280,395.

To all whom it may concern:

Be it known that I, KENNETH HOWIE, a citizen of the United States, and resident of Philadelphia, Pennsylvania, have invented 5 certain new and useful Improvements in Take-Up Mechanism for Knitting-Machines, of which the following is a specification.

My invention is an improvement upon that 10 form of takeup mechanism disclosed in Letters Patent of the United States granted to Wildman Mfg. Company, No. 940,656, November 23rd, 1909, as assignee of G. L. Ballard.

The present invention consists in the features and combination and arrangement of parts hereinafter described and particularly pointed out in the claims.

In the accompanying drawing:

Figure 1 is a side elevation of takeup 20 mechanism embodying my invention.

Fig. 2 is a front view of one of the hangers with the takeup roll in place illustrating the driving mechanism, and my present attachment.

Fig. 3 is a sectional view through the weight and lever.

Fig. 4 is a front view of another form of the invention.

In these drawings the takeup rolls 1, 1, are 30 journaled in arms 3, which are fixed by set screws to the rod, or shaft 5, journaled in standards, of a main or rotary frame one of which is shown at 6. These arms constitute a movable support for the take-up rolls. One 35 of the takeup rolls carries a worm wheel 10 driven from a worm 9, the latter being driven through friction members 20, 22, associated with the shaft 17. The shaft 17 is driven from the takeup ring in the usual 40 manner through a gear wheel 17^x. One of the arms of the pivoted frame 3 which carries the takeup rolls and is connected to the cross-shaft 5 is connected by a link 11 with a lever 12 pivoted to a bracket 13 at 13', said 45 bracket being fixed to the hanger or standard 6. This lever carries a screw 15 bearing on the rod 16, which has a key 18 extending through slots in the hub of the upper friction drive member 20 and through this key downward pressure is exerted on the friction member 20, and this pressure is transmitted to the friction clutch disks between the upper member 20 and the lower member 22, and as the latter is connected with the worm 9 the said

worm will be driven more or less according 55 as the pressure increases or diminishes at the clutch disks. In the patent above referred to a spring 12^x is shown for pressing the lever 12 downwardly, this spring being adjustable as to pressure by means of a screw 23, so that 60 the operator is enabled to change the stress to which the parts are subjected to set the apparatus for different grades of yarn or different degrees of tension on the fabric, it being noted that the pressure of the spring 65 12^x was in the same direction that gravity acted upon the takeup frame 3 with its takeup roll.

While the spring just mentioned provided 70 an operative construction there are objections to use of a spring in connection with a takeup mechanism for a knitting machine, owing to changes in temperature affecting the stress under which the parts are placed by said spring and it has been found that a 75 spring does not act with the required degree of sensitiveness and responsiveness when the machine is started up after a period of rest.

In carrying out my present improvement 80 I employ a beam carrying an adjustable weight after the manner of a scale beam. This beam is indicated at *a* pivoted at *b* to a lug *c* built onto or formed with the bracket or main rotary frame 6, the lower edge of the 85 beam near its pivotal point resting upon the boss *d* forming a part of the pivoted frame in which the takeup rolls are mounted. This boss may be provided with a portion *e* of slightly reduced diameter upon which the 90 scale beam rests. This scale beam extends parallel with the takeup rolls and lies comparatively close to the front takeup roll, so that the weight shown at *f* carried by the beam will be located near the vertical axial 95 center of the machine about which the takeup mechanism rotates and thus the scale beam, together with the weight will not tend in any material measure to throw the revolving parts out of balance and it will not be 100 subjected to an undesirable degree to the action of centrifugal force. The scale beam may be graduated as indicated and the weight is adjustable along this beam and may be held in any adjustable position by the 105 screw *g* passing through the weight member and having its end bearing in a groove in the scale beam. By adjusting the weight along

the beam different degrees of stress can be applied to the movable takeup frame to suit the conditions of the work being done, as for instance, different grades of yarn or different degrees of tension as may be desired on the fabric.

This scale beam and weight adjusting mechanism will not be subject to variation because of changes in temperature and it will immediately respond to any position of adjustment whether the machine has been running for some time or has been at rest for a period more or less extended.

While I have shown the improvement in connection with a takeup of the revolving type, that is one which revolves with the knitting head, it may be employed with a takeup of a fixed character or in other words one which does not revolve.

The construction lends itself to preserving a compact form of takeup mechanism and an adjustment which readily is accessible by the operator.

Referring to the multiple disk friction clutch it will be noticed that one set of friction disks is of fiber and the other set of steel, and these are marked respectively 24 and 25.

The fiber disks are all connected with the upper member of the friction and the steel disks are connected with the worm member. In order to prevent oil from getting to the steel and fiber disks a shield is provided at 26, forming an extension of the upper friction clutch member 20 and reaching down within the lower clutch member, which latter has a rim or flange 27 reaching to near the under side of the upper member 20. This depending shield will prevent the oil from reaching the clutch disks.

As shown in Fig. 4, the weight instead of being movable for adjusting the tension, is maintained at one point as near to the axial center of the machine as possible. The weight f' is therefore fixed at the end of the lever or beam a' which like the beam a is pivoted to a boss at c .

The bearing upon which this lever or beam rests, instead of being fixed as in the form first described, is shiftable. This bearing consists of a roller d' on a block or bracket d^2 adjustably mounted on the graduated rod j . This rod extends parallel with the takeup rolls and is fixed to arms 3 of the takeup frame which, as above described, pivots about the axis of the rod or shaft 5.

By adjusting this bearing along under the weighted lever or beam the gravitating force of the weight will be imparted to the pivoted takeup frame in greater or lesser degree as desired to thereby vary the driving capacity of the clutch.

Reverting to the advantages of the weight and weight beam as compared to a spring for applying tension to the parts it may be

further pointed out that the use of a spring is undesirable in combination with clutch employing members, such as fiber washers, which are affected by atmospheric conditions.

If the atmosphere is damp the fiber absorbs moisture, particularly when the machine is idle for any length of time, as over night. The swelling of the fiber of course requires that the takeup frame must lift higher in order to release the clutch. The higher the takeup frame has to go in order to release the clutch the more the spring will be compressed and consequently the greater will be the reaction of the spring upon the takeup frame and the pull of the frame upon the fabric. As an example say that the expansion in the clutch is an eightieth of an inch due to absorbing moisture, the extra compression of the spring is such that the spring's reaction increases the pull of the takeup frame from 32 pounds to 56 pounds, which of course is objectionable. With the weight arrangement, however, it makes no difference how high the takeup frame has to lift in order to release the clutch, because the gravitating action of the weight is always the same, not being affected by the expansion or contraction of the clutch members.

What I claim is:

1. In combination in a takeup for knitting machines, a pair of takeup rolls, a movable support therefor, driving means for the takeup rolls including a clutch, a connection from the movable takeup support for controlling the clutch and adjustable gravitating means for exerting pressure to vary the driving action of the clutch according to the demands of the work, said adjustable gravitating means including a weight, a pivotally mounted beam carrying the weight and exerting pressure upon the movable takeup support and through it upon the driving clutch, said beam extending in a plane substantially parallel with the takeup rolls.

2. In combination in a takeup for knitting machines, a rotary frame to rotate with the circle of needles, a pair of takeup rolls, a support therefor pivotally mounted in said rotary frame, driving means for the takeup rolls including a clutch, a connection between the pivoted frame and the clutch for controlling the latter and means for applying varying pressures comprising a weighted beam pivotally mounted and extending parallel with the takeup rolls, and means of adjustment for varying the gravitating force of the weight on the takeup frame, substantially as described.

3. In combination in a takeup mechanism for knitting machines, a revolving frame, to rotate with the circle of needles, takeup rolls, a support therefor movably mounted in the revolving frame, a clutch for driving

the takeup rolls, a connection between the movable roll support and the clutch and adjustable gravitating means carried by the revolving frame and exerting its force upon

5 the movable roll support, said gravitating means being maintained at substantially the same position relative to the axis of rotation of the revolving frame under all adjustments of said gravitating means, substantially as described.

4. In combination in a takeup mechanism for knitting machines, a revolving frame, to rotate with the needle circle takeup rolls, a support therefor movably mounted in the 15 revolving frame, a clutch for driving the takeup rolls, a connection between the movable roll support and the clutch and adjustable gravitating means carried by the revolving frame and exerting its force upon 20 the movable roll support, said gravitating means comprising a weighted beam pivoted to the revolving frame, extending substantially parallel with the takeup rolls, and an

adjustable bearing on the movable roll support on which the beam rests, substantially 25 as described.

5. In combination in takeup mechanism for knitting machines, a frame, takeup rolls, a movable support therefor mounted in the frame, connections for driving the takeup 30 rolls, including a clutch, a connection between the movable roll support and the clutch for varying the driving capacity of the latter, a weighted beam pivoted to the frame and extending in a plane substantially parallel with the takeup rolls, a rod 35 carried by the movable roll support and a bearing adjustable along said rod and engaged by the weighted beam, whereby the gravitating force of said beam exerted upon 40 the movable support may be varied to vary the driving capacity of the clutch, substantially as described.

In testimony whereof, I affix my signature.

KENNETH HOWIE.
